UNITED STATES PATENT OFFICE.

GEORGE R. WARD, OF NEW YORK, N. Y., ASSIGNOR, BY MESNE ASSIGNMENTS, TO THE UNION BAG & PAPER COMPANY, A CORPORATION OF NEW JERSEY.

PULP-MOLDING MACHINE.

No. 827,765.

Specification of Letters Patent.

Patented Aug. 7, 1906.

Application filed December 26, 1901. Serial No. 87,242.

To all whom it may concern:

Be it known that I, GEORGE R. WARD, a citizen of the United States, residing at New York, N. Y., have invented certain new and 5 useful Improvements in Pulp-Molding Machines, of which the following is a clear, full, and exact description.

My invention relates to a machine for forming articles from a suitable pulp; and my object is to improve the construction of such machines.

My invention will be defined in the claims.

In the drawings showing the preferred embodiment of my invention, Figure 1 is a plan view; Fig. 2, a side elevation, parts being in section. Fig. 3 is a central sectional view; Fig. 3^a, a detail sectional view on line x x of Fig. 3. Fig. 4 is a partial section of a modification, parts being omitted; and Fig. 5 is a 20 section on line y y of Fig. 4.

In the above preferred embodiment, 1 is the base on which the parts are mounted, and 2 is a support extending therefrom.

3 is a traveling mold-face, preferably 25 perforated, as shown. In order to move this face, I have in this embodiment provided a vertical shaft 4, which may be rotated intermittently or step by step by means of a roller 5 on wheel 6, which roller enters slots in a 30 star-wheel 7, fixed to the shaft, as shown in Figs. 1 and 2. The shaft 4 may carry a hollow circular head 8, on which the mold-face 3 is carried by a hollow extension 9, communicating with both the circular head and the 35 perforated mold-face.

In order to apply a layer of pulp to the mold-face, I preferably provide a stationary vat 10, containing a suitable pulp, as shown. In the present embodiment I have provided 40 an auxiliary pulp-holder 11 in said vat, which normally stands below the level of the pulp in the vat and is raised up to said mold-face, as shown in dotted lines in Fig. 3, carrying with it a quantity of pulp. The mold-face enters 45 the pulp-holder 11, as shown in dotted lines in Fig. 3.

13 is a hollow shaft at all times in communication with hollow head 8, as shown in Fig. 3, by which the air may be exhausted to produce a suction through the perforated mold-face 3 by means of a pump 14 or other suitable device.

The auxiliary pulp-holder 11 is reciprocated by a plunger 15, carried on a sleeve 16,

having pins 17 thereon. A cam-wheel 18, 55 fixed on the shaft 19, engages a roller 20 on lever 21 and rocks the same on pins 22, which lie in a slot in shaft 19, as shown in Fig. 2. The rock-lever 21 has two legs which embrace sleeve 16 and lie beneath pins 17, by 60 which the sleeve and parts carried by it are raised to the proper height. The slotted wheel 7 then rotates the mold-face 3 a quarter-turn, and as I preferably provide on head 8 a number of mold-faces similar to the face 3 (four in the present embodiment) a new face 65 is brought into the position shown in Fig. 2. A second mold-face 23, (shown in dotted lines in Fig. 2,) carried by sleeve 16, may be provided, which registers with mold-face 3 in 70 its new position and by which the layer of pulp on the mold-face may be compressed to form the article at the same time that a layer of pulp is applied to the succeeding face. The sleeve 16 then sinks again, and the star-wheel turns head 8 another quarter-turn, 75 bringing face 3 into the position shown at the right of the figures.

24 represents spring-pressed valve-stems carrying valves to close or open communication between the mold-faces and the suction device 14. 25 is a cam-ring attached to hollow shaft 13 for regulating the action of these valves.

26, Fig. 3, is a lever fixed to hollow shaft or 85 pipe 13 and having a roller-stud 27 sliding in a cam-groove 28 in the lower face of a wheel 29, by which when the face 3 arrives at the point shown at the left of the figures the cam-ring 25 is slightly moved from right to left in 90 Fig. 2 and depresses the valve at the left of the figure from the closed position shown to the open position shown in Fig. 3. The valve remains open until just before the face reaches the position at the right of the figures, when 95 the cut-away portion of the ring, Fig. 2, releases the stem and allows the valve to close.

30 30 are hollow pipes leading to and carried around each of the perforated faces and which successively register with an opening 31 in an extension 32 from pipe 13 (see Fig. 3^a) 100 when the cam-ring is given the slight movement above described.

32^a is a plug preventing communication between pipes 13 and 32. This pipe 32 communicates with a compression-pump 33 or other suitable device, by which a blast of air is blown through the mold-face and the 105

formed article loosened from the mold-face or, if preferred, blown off from the mold-face.

In Fig. 4 I have shown an alternative form of construction, the actuating mechanism being omitted. I have provided a reticulated mold-face 34, which may both supply the pulp to the mold-face 3, and also partially form the article, if preferred. The plunger 36 may carry a reticulated basket 37 and may slide on a fixed tube 38, communicating with the suction device 14. This pipe is closed by valve 39 until the finger 40 strikes the lower end of the valve-stem 41 as the plunger rises, thus applying suction through basket 37 (which is then above end of the pipe) until after the basket or face has been pressed against the face 3 and has moved downward away from the same to loosen or remove the article from the mold-face. This basket 37 therefore acts as a receiving-face for the plate, and when said face is pressed against the pulp-dish on the face 3 and suction is applied through the receiving-face 37 the dish will be removed from the face 3 without damaging the dish. Faces 3 and 37 are shown as nesting with each other, the face 37 being a counterpart of face 3.

I am aware that many variations may be made from the construction above described without departing from the scope of my invention as claimed, and I therefore do not desire to be limited to the embodiments herein described and illustrated.

What I claim is—

35 1. In a pulp-machine in combination a traveling mold-face and means to move the same, a receptacle containing a suitable pulp, means to move said receptacle up to said mold-face to supply a layer of pulp thereto, a second face shaped to conform to the shape of the article to be formed, and means to cause said faces to be moved together, one of said faces being perforated, and means to cause a draft of air to pass through said perforated face when said faces are in contact, to remove the article from said first face and transfer it to said second face.

2. In a pulp-machine in combination a traveling mold-face and means to move the same in a substantially horizontal plane, a receptacle containing a suitable pulp, means to move said receptacle up to said mold-face to supply a layer of pulp thereto, a second face nesting with said first face, and means to cause said faces to move together, one of said faces being perforated, and means to cause a draft of air to pass through said perforated face when said faces are in contact, to remove the article from said first face and transfer it to said second face.

3. In a pulp-machine in combination a perforated mold-face, a pulp-receptacle for containing a suitable pulp, means to automatically give a relative movement between said face and receptacle to move the same

toward each other and cause said face to relatively dip into and rise from the pulp therein, a suction device to apply suction through said face when in said pulp whereby said face receives a layer of pulp, means to move said face and receptacle laterally of each other, a receiving-face at all times outside of the pulp in said receptacle, means to move said faces together, and means to cause a draft of air through one of said faces to transfer the article to said receiving-face.

4. In a pulp-machine in combination, a perforated mold-face, a pulp-receptacle for containing a suitable pulp, means to automatically give a relative movement between said face and receptacle to move the same toward each other and cause said face to relatively dip into and rise from the pulp therein, a suction device to apply suction through said face when in said pulp whereby said face receives a layer of pulp, means to move said face and receptacle laterally of each other, a perforated receiving-face at all times outside of the pulp in said receptacle, means to move said faces together, and means to cause a draft of air through said receiving-face to transfer the article to said receiving-face.

5. In a pulp-machine in combination, a perforated traveling mold-face, a pulp-receptacle for containing a suitable pulp, means to automatically give a relative movement between said face and receptacle to move the same toward each other and cause said face to relatively dip into and rise from the pulp therein, a suction device to apply suction through said face when in said pulp whereby said face receives a layer of pulp, means to move said face laterally of said receptacle and in a substantially horizontal plane, a receiving-face at all times outside of the pulp in said receptacle, means to move said faces together, and means to cause a draft of air through one of said faces to transfer the article to said receiving-face.

6. In a pulp-machine in combination a traveling mold-face, means to move the same, a relatively stationary pulp-vat and an auxiliary pulp-holder therein, and means to cause said pulp-holder to move up to said face to supply a layer of pulp thereto.

7. In a pulp-machine in combination a traveling mold-face, means to rotate the same, a relatively stationary pulp-vat and an auxiliary pulp-holder therein, and means to cause said pulp-holder to move up to said face to supply a layer of pulp thereto.

8. In a pulp-machine in combination a traveling mold-face, means to move the same, a relatively stationary pulp-vat and an auxiliary pulp-holder therein consisting of a reciprocating plunger, means to cause said pulp-holder to move up to said face to supply a layer of pulp thereto.

9. In a pulp-machine in combination a traveling mold-face, means to move the

- same, a relatively stationary pulp-vat and an auxiliary pulp-holder therein, means to cause said pulp-holder to move up to said face to supply a layer of pulp thereto, a second 5 mold-face located at a point farther on in the travel of said first face, and means to press said faces together to form said article.
10. In a pulp-machine in combination a perforated traveling mold-face, means to apply suction through the same, means to move said face, a relatively stationary pulp-vat and an auxiliary pulp-holder therein, and means to cause said pulp-holder to move up to said face to supply a layer of pulp thereto.
15. In a pulp-machine in combination a perforated traveling mold-face and means to apply suction through said face, means to move the same, a relatively stationary pulp-vat and an auxiliary pulp-holder therein, 20 means to cause said pulp-holder to move up to said face to supply a layer of pulp thereto, a second mold-face located at a point farther on in the travel of said first face, means to press said faces together to form said article,
- 25 means to separate said faces, and a device to blow a current of air through said perforated face to loosen the article from said face.
12. In a pulp-machine in combination a mold-face, a relatively stationary pulp-vat 30 and an auxiliary pulp-holder therein, means to cause said auxiliary pulp-holder to move out of said vat up to said face to supply a layer of pulp thereto, a second mold-face, and means to press said faces together to 35 form said articles.
13. In a pulp-machine in combination a pulp-vat, a substantially vertical shaft, means to rotate the same intermittently, a mold-face carried by said shaft and adapted 40 to stop over said vat, a reciprocating plunger in said vat carrying an auxiliary pulp-holder, means to raise said plunger and cause said mold-face to enter said pulp-holder, and means to cause a layer of pulp to adhere to 45 said mold-face.
14. In a pulp-machine in combination a pulp-vat, a substantially vertical shaft, means to rotate the same intermittently, a mold-face carried by said shaft and adapted 50 to stop over said vat, a reciprocating plunger in said vat carrying an auxiliary pulp-holder, means to raise said plunger and cause said mold-face to enter said pulp-holder, means to cause a layer of pulp to adhere to said 55 mold-face, and a second mold-face adapted to be pressed against it to form said article.
15. In a pulp-machine in combination a pulp-vat, a substantially vertical shaft, means to rotate the same intermittently, a 60 mold-face carried by said shaft and adapted to stop over said vat, a reciprocating plunger in said vat carrying an auxiliary pulp-holder, means to raise said plunger and cause said mold-face to enter said pulp-holder, means to cause a layer of pulp to adhere to said 65 65
- same, a relatively stationary pulp-vat and an auxiliary pulp-holder therein, means to cause said pulp-holder to move up to said face to supply a layer of pulp thereto, a second mold-face located at a point farther on in the travel of said first face, and means to press said faces together to form said article.
16. In a pulp-machine in combination a substantially vertical shaft and means to rotate the same, a plurality of perforated mold-faces carried thereby and means to create a suction through said faces, means to supply a layer of pulp to said faces in succession, a valve for each mold-face controlling the suction therethrough, and a cam device controlling said valves.
17. In a pulp-machine in combination a substantially vertical shaft and means to rotate the same, a plurality of perforated mold-faces carried thereby and means to create a suction through said faces, means to supply a layer of pulp to said faces in succession, a valve for each mold-face controlling the suction therethrough, a cam device controlling said valves, a relatively stationary mold-face adapted to register with said mold-faces in succession, and means to press said relatively stationary face against said other faces in 90 succession to form said article.
18. In a pulp-machine in combination a substantially vertical shaft and means to rotate the same, a plurality of perforated mold-faces carried thereby and means to create a suction through said faces, a pulp-vat and means to supply a layer of pulp therefrom to said faces in succession, a valve for each mold-face controlling the suction therethrough, a cam device controlling said valves, a relatively stationary mold-face adapted to register with said mold-faces in succession, and means to press said relatively stationary face against said other faces in succession to 95 form said article.
19. In a pulp-machine in combination, a traveling perforated mold-face, and means to cause the same to travel in a substantially horizontal plane, a receptacle for containing a suitable pulp, said receptacle being stationary relative to the horizontal direction of travel of said face, means to dip said face in the pulp therein, and a suction device to apply suction through said perforated face whereby said face receives a layer of pulp, a second mold-face nesting with said first face and located beyond and outside of said receptacle and relatively stationary with respect to the travel of said first face and adapted to register with said first face, and means to press said faces together to form the article.
20. In a pulp-machine in combination a traveling perforated mold-face, and means to cause the same to travel in a substantially horizontal plane, a receptacle for containing a suitable pulp, said receptacle being stationary relative to the horizontal direction of travel of said face, means to dip said face in the pulp therein, and a suction device to apply suction through said perforated face 130

whereby said face receives a layer of pulp, a second mold-face located beyond and outside of said receptacle and relatively stationary with respect to the travel of said first face and adapted to register with said first face, and means to press said faces together to form the article and separate said faces without removing the article from said first face, a receiving-face, and means to move said first face and said receiving-face together, and means to apply a draft of air through one of said faces to transfer said article to said receiving-face.

21. In a pulp-machine in combination, a perforated mold-face, means to supply a layer of pulp thereto, a suction device to apply suction through said face whereby it receives and retains a layer of pulp thereon, a second mold-face, means to press said faces together and separate the same to form the article without removing said article from said first face, a receiving-face and means to cause it and said first face to be moved against each other, and means to apply a draft of air through one of said faces to transfer said article to said receiving-face.

22. In a pulp-machine in combination, a perforated mold-face, means to supply a layer of pulp thereto, a suction device to apply suction through said face whereby it receives and retains a layer of pulp thereon, a second mold-face, means to press said faces together and separate the same to form the article without removing said article from said first face, a perforated receiving-face, and means to cause it and said first face to be moved together, and means to apply air-suction through said receiving-face to transfer said article to said receiving-face.

23. In a pulp-machine in combination, a perforated mold-face, a pulp-receptacle for containing a suitable pulp, means to automatically give a relative movement between said face and receptacle to move the same toward each other and relatively dip said face into and cause it to rise from said pulp, means to cause suction through said face when in said pulp whereby said face receives a layer of pulp, means to move said face and receptacle laterally of each other, a relatively stationary receiving-face located outside of said receptacle and adapted to nest with said first face, means to move said faces together, and means to cause a draft of air through one of said faces to transfer said article to said receiving-face.

24. In a pulp-machine in combination a perforated mold-face, a pulp-receptacle for containing a suitable pulp, means to automatically give a relative movement between said face and receptacle to move the same toward each other and relatively dip said face into and cause it to rise from the pulp, means to cause suction through said face when in said pulp whereby said face receives a layer

of pulp, means to relatively move said face and receptacle laterally of each other, a relatively stationary mold-face located outside of said receptacle and adapted to nest with said first face, means to automatically press said faces together, and means to transfer said article to said relatively stationary face.

25. In a pulp-machine in combination, a perforated mold-face, a pulp-receptacle for containing a suitable pulp, means to relatively dip said face into and cause it to rise from the pulp in said receptacle, and a suction device to apply suction through said face when in said pulp whereby said face receives a layer of pulp, means to automatically move said face and receptacle laterally of each other, a second mold-face located outside of said receptacle and shaped to conform to the article to be formed, means to automatically press said faces together to form said article and separate the same without removing said article from said first face, a receiving-face for said article, and means to move said first face and said receiving-face together, and means to apply a draft of air through one of said last two faces to transfer said article to said receiving-face.

26. In a pulp-molding machine in combination, a device to contain pulp, a mold consisting of an upper and a lower molding-face adapted to be pressed together, said upper face being perforated, means to cause a relative movement between said device to contain pulp and said upper face to immerse said face in the pulp and free it therefrom, said upper face being held substantially horizontal during said relative movement, a suction device which applies suction through said upper face when so immersed, and means to press said faces together to form the article.

27. In a pulp-molding machine in combination, a device to contain pulp, a mold consisting of an upper and a lower molding-face adapted to be pressed together, one of said faces being perforated, means to cause said device to contain pulp to move up to and down from said perforated face to immerse said face in the pulp and free it therefrom, a suction device which applies suction through said face when so immersed, and means to press said faces together to form the article.

28. In a pulp-molding machine in combination, a rotating mold-carrier having thereon a succession of perforated mold-faces, a pulp-holding receptacle and means to cause said faces to dip in succession into the pulp therein, a reciprocatable mold-face located outside said receptacle and adapted to nest with said other faces in succession, and means to press said reciprocating face against said other faces to compress the pulp thereon.

29. In a pulp-molding machine in combination, a rotating mold-carrier having there-

on a succession of perforated mold-faces, means to rotate the same intermittently, a pulp-holding receptacle and means to cause said faces to dip in succession into the pulp therein, means to apply suction through said faces in succession, a reciprocatable mold-face located outside said receptacle and adapted to nest with said other faces in succession when said carrier is at rest, and

means to press said reciprocating face against said other faces to compress the pulp thereon.

Signed at New York, N. Y., this 17th day of December, 1901.

GEORGE R. WARD.
